UNITED STATES PATENT OFFICE

WERNER SCHULZ, OF BERLIN, GERMANY, ASSIGNOR TO SIEMENS & HALSKE AKTIEN-
GESELLSCHAFT, WERNERWERK, OF SIEMENSSTADT, NEAR BERLIN, GERMANY

TELEPHONE SYSTEM

Application filed September 15, 1926, Serial No. 135,531, and in Germany September 26, 1925.

In telephone exchanges with which applicant is familiar hitherto all the traffic has passed over trunk positions, which were provided for this purpose with a trunk multiple field. To render the traffic more easily supervised and concentrated, it is proposed that, in future the through going calls are to pass over separate positions (switching through positions). The supervision of the conversation, however, is to remain at the trunk positions; hence it is better if the supervisory signals, hitherto used at the trunk positions, can be retained without any alteration or addition.

According to the invention, the new circuit of the switching through position with amplifiers is so arranged that no addition need be made at the existing position.

The drawing shows by way of example one method of arranging the circuit. The manner in which the traffic is dealt with will now be explained.

While the plugs FVS 1 and FVS 2 of the double cord circuit with amplifiers are in the multiple jacks of the existing trunk lines, such as FLTG 2', the plugs FS 1 and FS 2 of the cord circuit where supervision takes place are inserted in the jacks Kva 1 and Kva 2, thus connecting the plugs to the amplifier circuit in accordance with the invention. In known manner the amplifier is provided with relays RR 1 and RR 2, which are operated by ringing current received over the trunk line. These relays enable the call to be sent into the other trunk line by energizing the ringing current re-transmitting relays WR 1 and WR 2, they also enable signals to be sent to the trunk position by connecting up additional relays (FLR 1 and FLR 2).

If the trunk operator wishes to have a connection set up over amplifiers between two trunk lines, she communicates over an order wire with the switching through operator's position with amplifiers, and causes the switching through operator to connect at the multiple jacks her own trunk line to the wanted trunk line. The switching through operator gives the trunk operator the number of the amplifier cord circuit. The trunk operator then inserts the plug FS 2 of the trunk

cord circuit into the jack Kva 2, which is provided at all the trunk positions and is associated with the amplifier cord circuit. The following circuit is thus established:

1. Earth, battery, relay FHR 2, plug FS 2, 55 jack Kva 2, c-lead back contact pr 21, winding II of relay FLR 2, interrupter U, earth.

The interrupter U causes the relay FLR 2 to be operated in series with FHR 2, the lamp UL is flashed over the contact flr 21 as follows:

2. Earth, front contact flr 21, back contact er 23, lamp UL, battery, earth.

The relay FLR 2 also transmits current impulses over the a and b leads to the relay 65 FSR 2 in the trunk cord circuit:

3. Earth, battery, winding III of relay PR 2, front contact flr 25, a-lead, jack Kva 2, plug FS 2, key FRU 21, relay FSR 2 winding I, key FRU 22, plug FS 2, jack Kva 2, 70 b-lead, front contact flr 24, earth.

The supervisory lamp FSL 2 in the trunk cord circuit is flashed over:

4. Earth, front contact fsl 2, winding II of relay FSR 2, front contact fhr 21, lamp 75 FSL 2, battery, earth.

The switching through operator now inserts the plug FVS 2 into the multiple jack FKV 2 of the wanted trunk line and she inserts the plug FVS 1 into the multiple jack 80 FKV 1 of the calling trunk line. If the wanted trunk line be engaged, the relay PR 2 in the switching through cord circuit cannot operate, hence the supervisory lamp UL at the switching through position and the lamp FSL 2 at the trunk position continue to flash. When the wanted line becomes free, the relay PR 2 is operated over:

5. Earth, over the c-lead to the trunk line 85 jack FKV 2, plug FVS 2, windings I and II of relay PR 2, battery, earth.

On operating, the relay PR 2 at its contact pr 21 disconnects the relay FLR 2 from the c-lead of the supervisory line coming 95 from the trunk position, and at its front contact pr 23 it prepares a circuit for the relays DR 2 and ZR 2. The contact pr 22 closes a circuit for relay FLR 2 over:

6. Earth, battery, winding I of relay FLR 100

2, front contact *pr* 22, back contact *zr* 21, earth.

The relay is operated and at its contacts *flr* 24 it closes another circuit;

5 7. Earth, battery, relay FHR 2, plug FS 2, jack *Kva* 2, *c*-lead, front contact *pr* 23, relays DR 2 and ZR 2, front contact *flr* 24, earth.

The relay ZR 2 at its contact *zr* 23 disconnects the supervisory lamp UL at the switching through position, at its contact *zr* 21 it opens the circuit for energizing relay FLR 2 and it locks itself over its own contact *zr* 22. When the relay FLR 2 operated, it energized the relay FSR 2 at the trunk position (circuit 3) and the latter locks itself (circuit 4), because relay FHR 2 remains attracted. The supervisory lamp FSL 2 at the trunk position burns steadily to indicate that the wanted trunk line has become free. The trunk operator can now effect the switching over of her line in the multiple field at the amplifier position. She inserts the plug FS 1 belonging to the plug FS 2, which is in the jack *Kva* 2, into the jack *Kva* 1 associated with the amplifier cord circuit:

25 8. Earth, battery, relay FRH 1, plug FS 1, jack *Kva* 1, *c*-lead, back contact *pr* 11, winding II of relay FLR 1, interrupter U 1, earth.

30 The supervisory lamp FSL 1 now flashes in the same way as previously did the lamp FSL 2. If the trunk operator has released by withdrawing the plug from the answering jack of the trunk line (not shown in the drawing), the relay PR 1 at the switching through position with amplifier can then operate as follows:

35 9. Earth, *c*-lead, jack *Fkv* 1, winding II and I of relay PR 1, battery, earth.

40 The relay PR 1 is energized and over its contacts the following circuits are established:

45 10. Earth, battery, winding I of relay FLR 1, front contact *pr* 12, back contact *zr* 11, earth.

The relay FLR 1 is operated and its contacts *flr* 14 and 15 close a circuit for the relay FSR 1:

50 11. Earth, battery, winding III of relay PR 1, front contact *flr* 15, *b*-lead, jack *Kva* 1, plugs FS 1, key FRU 12, winding I of relay FSR 1, key FRU 11, plug FS 1, jack *Kva* 1, *a*-lead, front contact *flr* 14, earth.

The relays DR 1 and ZR 1 are now operated over the contact *flr* 11:

55 12. Earth, battery, relay FHR 1, plug FS 1, jack *Kva* 1, *c*-lead, front contact *pr* 13, relays DR 1 and ZR 1, front contact *flr* 11, earth.

60 The relays DR 1, ZR 1 and FSR 1 are energized, hence the lamp FSL 1 burns steadily. At the amplifier, the lighting relay ZR 3 is energized over the contacts *zr* 14 and *zr* 24:

65 13. Earth, battery, resistance SW 10, front contacts *zr* 14 and *zr* 24, relay ZR 3, earth.

The amplifier lamps are now lighted. The plugs FVS 1 and FVS 2 have been switched through to the amplifier over the contacts *dr* 11, 12, 13 and *dr* 21, 22, 23. If the operator wants to call the end stations, she actuates in known manner her ringing key FRU 11, 12 or FRU 21, 22:

70 14. Source of alternating current, key FRU 11, plug FS 1, jack *Kva* 1, *a*-lead, back contact *flr* 12, relay AR 1, back contact *flr* 13, *b*-lead, jack *Kva* 1, plugs FS 1, key FRU 12, source of alternating current.

75 Thereby the relays AR 1 or AR 2 are energized in the switching through cord circuit, and they energize the call transmitting relays WR 1 or WR 2.

80 15. Earth, battery, call transmitting relay WR 1, front contact *ar* 11, earth.

85 These relays over their contacts *wr* 11, 12 and *wr* 21, 22 send ringing currents to the particular trunk line. The ringing current arriving over the trunk line *Fltg* 1 operates the relay RR 1. This at its contact *rr* 11 operates the relay WR 2 in series with the relay HR 1.

90 16. Earth, battery, relay WR 2, front contact *rr* 11, relay HR 1, earth.

95 The relay WR 2 is operated, hence ringing current flows over its contacts *wr* 21, 22 in the other trunk line *Fltg* 2. The relay HR 1 energizes the relay FLR 1 over:

100 17. Earth, front contact *hr* 11, winding I of relay FLR 1, battery, earth, so that the relay FSR 1 in the trunk cord circuit is operated over the contacts *flr* 12, 13.

The relay FSR 1 locks itself over:

105 18. Earth, front contact *fsr* 1, winding II of relay FSR 1, front contact *fh* 11, lamp FSL 1, battery, earth.

110 The lamp FLS 1 burns steadily. In the same manner the lamp FSL 2 is lighted when ringing current arrives over the trunk line *Fltg* 2. At the end of the conversation, when the trunk operator releases the connection by withdrawing the plugs FS 1 and FS 2 from the jacks *Kva* 1 and *Kva* 2, the relays DR 1, ZR 1, DR 2, ZR 2 are deenergized. The amplifier is extinguished; the plugs are disconnected from the amplifier; the relay FLR 2 is again energized (circuit 6), and the supervisory lamp UL is lighted at the switching through position:

115 19. Earth, front contact *flr* 21, back contact *zr* 23, lamp UL, battery, earth.

120 The lamp UL is extinguished when the plugs of the amplifier cord circuit are withdrawn from the multiple jack of the trunk line.

What is claimed is:

1. In a telephone system, a trunking operator's position, a cord circuit at said position for extending calls, two trunk lines, means including said cord circuit for connecting said trunk lines together, a switching through operator's position, an amplifying cord circuit at said second position, amplify- 125

ing means in said cord circuit normally inoperative, means including said amplifying cord circuit for connecting said trunk lines together, terminals individual to said amplifying cord circuit at said first position, and means responsive to the connection of a trunking cord circuit with said terminals for rendering said amplifying means operative.

2. In a telephone system, a switching 10 through operator's position, an amplifying cord circuit at said position, two trunk lines, means including said cord circuit for connecting said trunk lines together, a trunking operator's position, terminals individual to 15 said amplifying cord circuit terminating at said trunking operator's position, a cord circuit at said trunking operator's position, for connecting with said terminals, and means in said trunking cord circuit for supervising 20 the connection.

3. In a telephone system, a switching through operator's position, an amplifying cord circuit at said position, a trunking operator's position, a cord circuit at said trunk- 25 ing position, two trunk lines, means including said trunking operator's cord circuit for connecting said trunk lines together, and terminals for use in case amplification is needed for the established connection for 30 connecting said trunk lines by way of said amplifying cord circuit and for connecting said trunking operator's cord circuit to said amplifying cord circuit whereby said trunking operator's cord circuit is used for super- 35 visory purposes.

4. In a telephone system, a switching through operator's position, an amplifying cord circuit at said position, trunk lines, terminals for connecting two of said trunk lines 40 over said cord circuit, a trunking operator's position, a cord circuit at said trunking position and means for connecting said last mentioned cord with said amplifying cord circuit for supervisory purposes.

45 5. In a telephone system, an operator's position, a cord circuit at said position for extending calls, a second operator's position, an amplifying cord circuit at said second position, means for establishing a connection 50 over said amplifying cord circuit, and branch connections extending from said amplifying cord circuit to said first position for connecting said first cord circuit with said amplifying cord circuit in such a manner that the 55 first cord circuit is used for supervisory purposes.

6. In a telephone system, a plurality of circuits any one of which may be used trunks, amplifying and non-amplifying cord 60 to the exclusion of the others as a link interconnecting two trunks, supervisory means associated with said non-amplifying cords, a branch from each amplifying cord terminating in a jack, and means responsive to 65 the insertion of a plug of a non-amplifying

cord into the jack of an amplifying cord for rendering the supervisory means of the associated non-amplifying cord effective to indicate conditions of connections over the associated amplifying cord.

7. In a telephone system, a plurality of trunks, amplifying and non-amplifying cord circuits any one of which may be used to the exclusion of the others as a link interconnecting two trunks, supervisory means associated with said non-amplifying cords, two branches from each amplifying cord terminating in jacks, and means responsive to the interconnection of the two jacks of any amplifying cord by a non-amplifying cord 75 for rendering the supervisory means of the associated non-amplifying cord effective to indicate conditions of connections over the associated amplifying cord.

8. In a telephone system, a cord circuit 85 including normally inoperative amplifying means, means for connecting said cord circuit as a link in a telephone connection, a branch extending from said cord circuit and terminating in a jack, and means responsive 90 to the extension of a connection to said branch by way of said jack for rendering said amplifying means effective.

9. In a telephone system, a plurality of trunking operator's positions, a switching-through operator's position, trunk lines multiple connected to jacks at each of said first mentioned positions and at said second mentioned position, cord circuits at each of said first positions for interconnecting said 100 trunk lines, amplifying cord circuits at said switching-through operator's position for interconnecting said trunk lines, and multiple connections from said amplifying cord extending to each of said first mentioned 105 operator's positions.

10. In a telephone system, a plurality of trunking operator's positions, a switching-through operator's position, trunk lines multiple connected to jacks at each of said first mentioned positions and at said second position, cord circuits at each of said first positions for interconnecting said trunk lines, an amplifying cord circuit at said switching-through operator's position for interconnecting said trunk lines, multiple connections from said amplifying cord extending to each of said first mentioned operator's positions, and means at each of said first mentioned operator's positions each controlled over one of said cords at said trunking operator's position for supervising connections over the amplifying cord.

11. In a telephone system, a plurality of trunk lines, a link circuit for establishing a connection between two of said trunk lines, a branch from said link circuit, a source of characteristic current, and means in said link circuit, when a connection between two trunk 125 130

lines is established as set forth, responsive to a signal current applied to one of the connected trunk lines or to said branch for connecting said current source to the other trunk line.

12. In a telephone system, a plurality of trunk lines, a link circuit for establishing a connection between two of said trunk lines, two branches from said link circuit, a source of characteristic current, means in said link circuit controlled over one or the other of said branches for connecting said current source to one or the other of said trunk lines connected as set forth, and means responsive to the application of a signal current to either trunk line for reconnecting said current source to the other trunk line.

13. In a telephone system, a plurality of trunk lines, a first link circuit, a second link circuit, means including either one of said link circuits for connecting said trunk lines together, two branches from said first link circuit, and means for connecting said second link circuit to said branches for supervisory purposes when said first link circuit is used for establishing a connection as set forth.

In witness whereof, I hereunto subscribe my name this 21st day of August, A. D. 1926.
